UNITED STATES PATENT OFFICE

2,691,400

FISHERMAN'S UTILITY BAG

Peter A. Giordano, White Plains, N. Y., assignor
of twenty-five per cent to Jack P. Giordano,
White Plains, N. Y.

Application October 6, 1952, Serial No. 313,300

3 Claims. (Cl. 150—28)

1

This invention relates to new and useful improvements and structural refinements in bags and the principal object of the invention is to provide a general utility bag particularly adapted for use by fishermen in storing and carrying fish lures, hooks, leaders, knives and other fishing accessories.

Some of the advantages of the invention reside in its simple and durable construction, in its convenient operation and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention;

Figure 2 is front elevational view thereof with the closure flap in its open position;

Figure 3 is a sectional view, taken substantially in the plane of the line 3—3 in Figure 1;

Figure 4 is a fragmentary sectional view, taken substantially in the plane of the line 4—4 in Figure 2;

Figure 5 is a fragmentary front elevational view, similar to that shown in Figure 2 but with portions of the bag partly broken away so as to reveal its construction, and

Figure 6 is a fragmentary sectional detail of a removable receptacle and its attaching means, as used in the invention.

Like characters of reference are employed to designate like parts in the specification and throughout the several views.

Referring now to the accompanying drawings in detail, the invention is designated generally by the reference character 10 and embodies in its construction a bag having a back wall 12, a front wall 14, a connecting edge wall 16 and a closure flap 18.

The bag is provided with a suitable shoulder strap 20 which is stitched to opposite sides of the edge wall 16 and a pocket 22 is secured to the rear surface of the back wall 12 and is substantially coextensive therewith. A closure flap 24 is provided for the pocket 22 on the upper edge portion of the back wall 12, this flap being secured in a seam 26 whereby the aforementioned closure flap 18 is also secured to the back wall.

A transversely elongated pocket 28, provided at the front thereof with an inspection window 30, is disposed forwardly of the back wall 12 and is mounted in place by the aforementioned seam 26,

2

the pocket 28 being provided at the top thereof with an openable flap 32 which is retained in a closed position by a plurality of fasteners 34.

The upper edge of the front wall 14 is spaced downwardly from the upper edge of the back wall 12 so that when the flap 18 is opened, the pocket 28 becomes readily visible and accessible.

A downturned flap 36 is secured to the front surface of the upper edge portion of the front wall 14 and carries a fastener element 38 for coaction with a fastener element 40 on the closure flap 18 so as to sustain the latter in a closed position.

The flap 18 is preferably constructed from several superposed layers of material 18a, 18b, 18c, and the top portion of the flap has the layer 18c thereof provided with transversely extending, doubled and stitched ribs 42. Similarly, the layer 18a of the flap is provided with a plurality of spaced, transversely extending ribs 44, the purpose of the ribs 42, 44 being to add a certain degree of rigidity to the top portion of the flap.

If desired, the interior of the bag may be equipped on the front face of the back wall 12 with a plurality of stitched straps or strips 46, 48 functioning as holders for various different articles such as fishing leaders et cetera.

A relatively small pocket 50 is stitched to the front surface of the front wall 14, this pocket being provided at the front thereof with an inspection window 52 and the upper edge of this pocket being disposed under the aforementioned flap 36.

A removable receptacle 54 is superposed on the pocket 50 and has a front wall provided with an inspection window 56. The receptacle 54 also has a closure flap 58 provided with an inspection window 60 which is substantially registrable with the window 56, and it will be noted that a transversely elongated fold 62 is provided at the junction of the flap 58 with the upper edge of the receptacle proper, this fold accommodating an angulated keeper hook member 64.

The latter is removably engageable with the upper edge portion of the pocket 50 and is sustained in engagement therewith by the flap 36 which overlies the same. However, by simply lifting the flap 36 upwardly, the keeper hook member 64 may be disengaged from the pocket 50 to facilitate expeditious removal of the receptacle 54. Thereupon, the receptacle may be attached, by means of the same keeper hook member 64, to the belt of trousers, or the like, if so desired.

Needless to say, with exception of the hook member 64 which is formed from wire, the entire

bag is preferably constructed from flexible material possessing moisture resistant characteristics.

It is believed that the advantages and use of the invention will be clearly understood from the foregoing disclosure and accordingly, further description thereof is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. In a bag, the combination of an upstanding wall, a flap secured to the upper edge thereof, a pocket provided on said wall and having its upper edge disposed under said flap, a removable receptacle superposed on said pocket, and means on said receptacle for attaching the same to the upper edge portion of said pocket, said means including a transversely elongated fold, and a keeper hook engaged in said fold detachably engaging said upper edge of said pocket.

2. A bag comprising a back wall, a front wall having its upper edge spaced downwardly from the upper edge of said back wall, a closure flap including a top portion secured to said back wall and a depending front portion extending over said front wall, a pocket on said front wall, a pocket flap secured to said front wall and overlying the upper edge of said pocket, a removable receptacle superposed on said pocket, and means on said receptacle for attaching the same to the upper edge portion of said pocket, said means including a transversely elongated fold, and a keeper hook engaged in said fold detachably engaging said upper edge of said pocket, said closure flap over-

lying said pocket flap and said means to provide protection against accidental disengagement of said keeper hook.

3. A bag comprising a back wall, a front wall having its upper edge spaced downwardly from the upper edge of said back wall, a closure flap including a top portion secured to said back wall and a depending front portion extending over said front wall, a pocket on said front wall, a pocket flap secured to said front wall and overlying the upper edge of said pocket, a removable receptacle superposed on said pocket, and means on said receptacle for attaching the same to the upper edge portion of said pocket, said means including a transversely elongated fold, and a keeper hook engaged in said fold detachably engaging said upper edge of said pocket, said closure flap overlying said pocket flap and said means to provide protection against accidental disengagement of said keeper hook, including two superposed layers of material each having ribs provided thereon, the ribs on one layer being staggered from the ribs on the other layer for rigidifying said closure flap, said receptacle, and said pocket having aligned transparent windows enabling inspection of the contents of said pocket and said receptacle.
